UNITED STATES PATENT OFFICE.

ELMER Z. BURNS, OF MADISON, NEW JERSEY, AND GEORGE KEILLER, OF NEW YORK, N. Y.

AUTOMATIC DRAFT CONTROLLER.

Application filed October 8, 1920. Serial No. 415,510.

To all whom it may concern:

Be it known that we, ELMER Z. BURNS, a citizen of the United States, residing in Madison, county of Morris, State of New Jersey, and GEORGE KEILLER, a citizen of the United States, residing in New York, county and State of New York, have invented a certain Improvement in Automatic Draft Controllers, of which the following is a specification.

Our present invention relates principally to means whereby the supply of air to the furnace of a steam generator may be automatically governed by changes in the pressure of the steam generated, for the purpose of maintaining such pressure as nearly constant as possible within predetermined limits, although also applicable to water gates or other power modifiers.

The principal object of the invention is to provide a simple and relatively inexpensive apparatus for the purpose named, which shall be easy to assemble and to keep in order, and adaptable to plants already constructed, without any material or expensive changes. Our improved apparatus takes up very little room, is very flexible and lends itself to a great variety of embodiments or modifications.

By way of example, we have illustrated a preferred form of our apparatus in the accompanying drawings wherein Figure 1 is a diagrammatic view showing the general mechanical arrangement of the entire system, Figure 1^a is a modification of the draft controlling means shown in Figure 1, Figure 2 is a diagram of the electrical features of the apparatus, Figure 3 is an isometric view of the initial contact making and circuit reversing apparatus, Figure 4 is a plan view of certain details of the circuit reversing switch and Figure 5 is a plan view of the switch group shown at the top of Figure 3.

In Figure 1, the boiler whose draft is to be controlled is indicated at 10, the stack being indicated at 11. Our invention relates to automatic motive means, controlled by variations in steam pressure, temperature, speed or the like, which means may be

applied to the appropriate operation of a variety of draft modifying devices or other regulators, without departing from the scope of the invention. As an illustration of the universal nature of the invention, we have shown in Figure 1 two alternative forms of draft modifiers either of which can be operated by the motive means which forms the subject matter of our invention.

In the preferred form shown the immediate motive agent is the reciprocating rod 12, although it is obvious that other forms of movable impelling device may be used as equivalents. The rod 12 is screw-threaded and carries a sleeve 13 at one end which slides upon a guide 14, while the other end of the rod slides in guides 15 between which is placed a revoluble nut 16, provided with a worm-wheel 17, driven by a worm 18 on the armature shaft of an electric motor 19. As this nut is revolved in one direction or the other, the impelling rod 12 will move to the right or left in Figure 1.

In one alternative form shown in Figures 1 and 1^a the rod 12 is mechanically connected with the movable member of a switch or circuit controller 20, by means of which the operation of the electric blower 21 is regulated. This blower supplies forced draft to the furnace of the boiler 10 through the pipe 22.

In the other form (shown in Figure 1^a) connection is made preferably through a stiff spring 22' with a swinging damper 23 in the outgoing flue 24, whereby the draft is modified in a well known manner.

The operation of the electric motor 19 which actuates the impelling device 12 is accomplished by a main lever whose movements are made dependent upon changes in the steam pressure in the boiler 10. In the preferred form shown, this lever controls a series of initial circuit makers and reversing switch.

The main lever 25 is fulcrumed at 26 and an arm 27 on this lever has a pin 28 which projects through a slot 29 at the upper end of the bar 30, which is carried by the lever 31, fulcrumed at 32. This lever 31 is held in approximately the position indicated by 100

a knife edge 33 which is carried by the flexible diaphragm of a pressure gauge 34, connected by the pipe 35 with the boiler 10; and is therefore always subjected to the steam pressure present at any time within said boiler.

The steam pressure, tending to lift the lever 31 is balanced by a weight 36 on the arm 37, fulcrumed at 38, and by a properly calibrated spring 39. This latter supplies the element of variable tension necessary to regulate the balanced movements of the lever 31 between the upper and lower stops 40 and 41. It will be clear from the foregoing that an increase in steam pressure will produce a swinging movement of the switch lever 25 clockwise through the eccentric pin connection 28, bar 30 and lever 31, while a decrease in pressure will produce a contrary swing in the lever 25.

As shown in Figures 1 and 3, the main lever 25 controls a series of five initial circuit makers, held in a casing 42. One of these and parts of others are shown complete in Figure 3. The others are all like the one shown and are omitted for the sake of clearness.

Each initial circuit maker comprises a horizontal conducting shaft 43, turning very easily in its bearings, and held normally balanced in the position shown by the weight of the conducting plate 44 suspended beneath it, and the fact that its pivotal supports are located above its geometrical axis. This plate makes continual contact with the mercury mass 45. Near the front, the shaft 43 is provided with a transverse curved wire 46, normally out of circuit, but which makes contact at one end or the other with the mercury mass 47, whenever the shaft 43 is revolved one way or the other. These mercury masses or tanks 47 are arranged in staggered relation to conserve lengthwise space, as shown in Figure 5.

This movement, whereby contact is made at 47 is produced by the finger 48 striking one side or the other of the pin 49 which projects normally upright from the shaft 43. In order to insure completion of the operation called for by a given movement of the lever 25, as well as to prevent breaking of the full working current at the mercury surfaces (causing destructive arcs) we prefer to associate the series of initial circuit makers with a corresponding series of electromagnetic relays, shown at 50 in Figure 1 and fully described hereinafter.

The direction of rotation of the motor 19 is determined by the reversing switch, which is preferably constructed and operated as follows—

Within a casing 51 at the bottom of the lever 25 is placed a lightly turning shaft 52, similar to the shaft 43, but made of insulating material instead of metal. Under this

shaft, near the back is fixed a curved plate of metal 53 having a depending balancing projection 54 which is in constant contact with the mercury mass 55. The plate 53 is also provided with projecting wires 56, 57, 70, which are adapted to dip into the mercury masses 58 and 59 respectively, when the shaft 52 is tilted one way or the other. This shaft tends to return to normal under the action of the light spring 59.

At its forward end, the shaft 52 is similarly provided with the metal plate 60 having a depending portion 61 dipping constantly into the mercury 62, while the two wires 63 and 64, may dip into mercury 80 masses 65 or 66, according to which way the shaft 52 is tilted.

The tilting one way or the other of the shaft 52 is accomplished by the action of any one of the five pins 67 on the arc 68, 85 carried by the lever 25, when it presses one way or the other on the normally upright pin 69, fixed to the shaft 52.

It will be understood that the parts are so arranged and proportioned that the beginning and ending of contact between the finger 48 and any one pin 49 are coincident with the beginning and ending of contact between the pin 69 and a corresponding pin 67 on the arc 68.

In order that when contact is once made in the reversing switch it may certainly be preserved until completion of the desired automatic operation, a piece of steel or iron 70 is fixed under the middle of the shaft 100 52 and is presented to the contiguous pole of one or the other of the electromagnets 71, 72, hereinafter described.

From the above it will be clear that the tilting of any of the series of initial circuit makers in either direction will cause electrical connection between the two mercury masses belonging to that switch. On the other hand the tilting of the reversing switch clockwise will connect the mass 62 with the 110 mass 66 and the mass 55 with the mass 59; while counter-clock movement will connect 62 with 65 and 55 with 58.

While the movement of the impelling means is initiated, by means thus far described, any such movement is automatically limited, and the apparatus is brought to rest, preferably by the following means.

Along the path of movement of the rod 12 is located a series of circuit-opening 120 switches. As shown in Figure 1, there are seven of these, of which five correspond to the five initial circuit makers and the two at opposite ends of the series supply limiting means, whereby excessive travel of the 125 impelling means in either direction is prevented.

The circuit-opening switches are numbered from 73 to 79, and are carried upon a bar or shelf 80, upon which each switch 130

may be shifted, being secured in adjustable position by screws as shown. The roller 81 carried by and moving with the rod 12, is adapted to open any switch under which it comes during its travel, and in whichever direction said roller is moving.

It has been found in practice that the degree of change in position of certain forms of draft controller (for instance a damper 23) is not the same for all actual positions. The amount of movement which should be imparted to such a controller in a given position is determined by experiment, having in view particularly the maintenance of a maximum CO_2 output. Once having determined this, the switches 73 to 77 can be adjusted so that they may act to interrupt the movements of the impelling device or rod 12 at appropriate positions of the draft controller. This adjustability is an important feature of the invention.

The operation of the entire apparatus may now be described, with reference to Figure 2, wherein are shown the electric circuits involved. We shall describe the operation with respect to a single set of circuits only, as what is said regarding one position is true of all.

It is assumed that a lowering of steam pressure has caused the lever 25 to swing anti-clockwise, thus tilting the shaft of the initial circuit maker 82, and producing, therefore, a clockwise movement of the reversing switch shaft 52.

35 The field-magnet coils 83 of the motor 19 are, as shown, permanently connected with the mains 84, 85. Upon closure of the initial circuit at 82, the motor armature 86 will be energized as follows—

40 From 84, through 79, by magnet 71, mercury 66, 62, armature 86 (right to left) wire 87, starting resistance, 88, wire 89, temporary coil 90 on one of the series 50 of relay magnets, wire 91, switch 82, wire 92, circuit-opening switch 76, wire 93, mercury 55, 59, wire 94, mercury 65, wire 95 to main 85.

This will cause the rod 12 to move in the direction of the arrow in Figure 2, causing the damper to open more widely, or 50 an equivalent effect to be produced in any other type of draft controller that may be adopted.

The low resistance current thus set to work will operate through the relay 90 to 55 close the switch 96, which will short-circuit the resistance 88, the temporary coil 90 and the switch 82, through the low resistance coil 97. If, therefore, the lever 25 moves far enough to release the switch 60 82, only a small current on a branch circuit will be interrupted, avoiding all arcing, and the main current will be maintained by the coil 97, until opened by the roller 81 coming under the switch 76.

65 In Figure 2 the switch 75 is shown open,

as left at the end of a prior movement of the apparatus. It is, of course, understood that all of the switches 73 to 79 are automatic and close of themselves when freed from the pressure of the roller 81.

70

As is apparent from Figure 2, any movement of the main lever 25 clockwise, due to increase of steam pressure, will set up a current through the armature 86 from left to right in Figure 2, thus reversing the 75 motor and producing a limited movement to partly close the damper (or to produce an equivalent draft-controlling effect.) For instance, assuming the operation last described to have been completed, the lever 80 25 being to the left of the switch 82 and the roller 81 having moved to the right in Figure 2 far enough to open the switch 76. Now, if the steam pressure increases and moves the lever 25 clockwise (and therefore the shaft 52 anti-clockwise) this lever 85 25 will move past the switch 82 which is now dead, owing to switch 76 being open, until the next switch to the right of 82 will be closed, when the following circuit will 90 be established.

From 84, through the limiting switch 73 to magnet 72, mercury 58, shaft 52, mercury 55, wire 93, switch 75, switch just closed to the right of 82, magnet 90 directly above 95 switch 75, wire 89, resistance 88, wire 87, armature 86 (left to right) mercury 62, mercury 65, wire 95, and out at 85.

It will be seen that our invention provides an automatic motive mechanism whereby 100 the draft controller can be operated in either one of two directions from any position except fully opened or fully closed, in which case it can always be moved in one direction. Furthermore this movement is 105 a limited one not involving complete opening or closing, and it is variable in extent, being automatically limited at the end of one, two or more steps according to circumstances. In addition to these advantages, the adjustability of the circuit-openers along their support 80 makes it possible to operate by steps of adjustable length, calculated in different positions to correspond to movements of maximum efficiency 110 for each position, as determined by experiment.

It is a further advantage of our invention that, by using the relays 50 and the switch-retaining magnets 71 and 72, the definite 115 completion of a particular step is assured despite possible irregularities in the movement of the main lever 25, or its equivalent, due to steam surging or other accidental causes.

120 While our invention is principally useful in connection with systems wherein the draft control is made dependent upon variations in steam pressure, we do not confine ourselves to this field, since it is obvious that the 130

main lever 25, or its equivalent, may be actuated by agencies, responsive to other changes than those of pressure, as for instance, to changes of temperature or changes of speed. 5 Consequently the expression "apparatus of the character described" as used in our claims is to be understood to refer to any automatic motive mechanism for the operation of shaft controllers, whatever the nature of the changes upon which operation depends.

Various changes or modifications may be made in the form and arrangement of our apparatus without departing from the scope 15 of our invention and we do not limit ourselves to the details herein shown and described.

What we claim is—

1. In apparatus for automatic draft control, a draft regulator, impelling means therefor, a reversible electric motor for driving said means in one direction or the other, a series of initial circuit closing switches, a switch operating device movable 25 along said series in either direction adapted to operate said switches to close circuit therethrough and through a part of said motor in whichever direction said device moves, pressure motive means for operating said 30 switch operating device, and a source of pressure dependent upon the draft regulated for actuating said pressure motive means.

2. Apparatus of the character set forth in claim 1 hereof in combination with a reversing switch for said motor operated by said switch operating device.

3. In apparatus as set forth in claim 1 hereof, a high resistance circuit comprising 40 branches each including a relay magnet coil and one of said initial circuit makers, and low resistance permanent branch circuits each including a relay coil and a magnetic switch operated by said relay coils successively, said permanent branch circuits being arranged in a short circuit around said initial circuit makers to prevent arcing, substantially as described.

4. In apparatus for automatic draft control, a draft regulator, impelling means therefor, a motor for driving the same in either of two directions, controlling means for causing step by step movement of said motor in either direction, a pressure motive 55 mechanism capable of acting in any position of the impelling means to operate said controlling means, and a source of pressure dependent upon the draft regulated for actuating said pressure motive mechanism.

5. In apparatus of the character described 60 an impelling device, step by step motive means for actuating the same and automatic interrupters for said motive means placed in a series along the path of movement of said impelling means and adapted to be op-

erated thereby, said interrupters being adjustable as to position, whereby the different steps may be varied in extent at will.

6. Apparatus of the character set forth in claim 5 hereof wherein the motive means is 70 a reversible electric motor and wherein the interrupters are normally closed circuit breakers.

7. In apparatus of the character described 75 an impelling rod mounted for longitudinal reciprocating movement, an electric motor adapted to actuate the same, a series of normally closed switches in the circuits of said motor, and a roller on said rod adapted to open said switches successively as it moves 80 along the series.

8. In apparatus of the character described in claim 7 hereof, a support for the switches extending parallel with said rod and means 85 for fixing the switches in different positions along said support at will.

9. In apparatus of the class described, an actuating electric motor, a tilting switch for reversing the same, electromagnetic means in circuit with said motor for holding the 90 tilting element of said switch in one extreme position or the other, a revoluble shaft for operating the tilting switch, an electro-magnet on each side thereof adapted to be brought automatically in circuit with said 95 switch, and an armature under said shaft adapted to be brought opposite the pole on one or the other of said electro-magnets when said shaft is tilted to operate the switch.

10. Apparatus of the character set forth in claim 1 hereof wherein each initial circuit closer comprises a light balanced revoluble shaft carrying circuit closing means and a normally upright pin, and wherein the main lever is adapted to sweep over said pins in either of two directions so as to depress them sufficiently to allow the main lever to move onward.

11. Apparatus of the character set forth in claim 1 hereof wherein each initial circuit closer comprises two mercury masses, a revoluble shaft mounted over the same, a depending conductive member on said shaft dipping constantly into one of said mercury masses, and a second conductive member on the shaft adapted to dip one end or the other into the other mercury mass when said shaft is tilted.

12. In apparatus of the character described, impelling means, a reversible electric motor for driving the same, a series of initial circuit closers for said motor normally in open circuit position and a swinging circuit reversing switch for said motor normally 120 in open position; in combination with a main lever fulcrumed between the reversing switch and circuit closers, said lever being adapted to operate said circuit closers successively by impact at one end of the lever,

and being provided with a number of pins at its other end for successive operation of said reversing switch.

13. In apparatus of the character set forth in claim 12 hereof, a finger at one end of the main lever for operating the circuit closers successively and an arc at the

opposite end having pins adapted to operate the reversing switch co-incidently with each operation of a circuit maker.

In testimony whereof we have hereto set our hands on this 5th day of October, 1920.

ELMER Z. BURNS,
GEORGE KEILLER
